Primary Examiner — Christian P. McLean(74) *Attorney, Agent, or Firm* — Terrile, Cannatti & Chambers(57) **CLAIM**

We claim the ornamental design for a display screen with a cognitive design graphical user interface, as shown and described.

DESCRIPTION

The FIGURE is a front view of a display screen with a cognitive design graphical user interface of the present invention.

The outermost broken line illustrates the display screen and forms no part of the claimed design.
